(57) **CLAIM**

The ornamental design for an ice crusher, as shown and described.

DESCRIPTION

FIG. 1 is a front perspective view of a first embodiment of an ice crusher showing my design.

FIG. 2 is a rear perspective view of the ice crusher in FIG. 1.

FIG. 3 is a front elevation view of the ice crusher in FIG. 1. FIG. 4 is a rear elevation view of the ice crusher in FIG. 1. FIG. 5 is a left side elevation view of the ice crusher in FIG. 1.

FIG. 6 is a right side elevation view of the ice crusher in FIG. 1.

FIG. 7 is a top plan view of the ice crusher in FIG. 1.

FIG. 8 is a bottom plan view of the ice crusher in FIG. 1. FIG. 9 is a front perspective view of a second embodiment of the ice crusher.

FIG. 10 is a rear perspective view of the ice crusher in FIG. 9.

FIG. 11 is a front elevation view of the ice crusher in FIG. 9.

FIG. 12 is a rear elevation view of the ice crusher in FIG. 9. FIG. 13 is a left side elevation view of the ice crusher in FIG. 9.

FIG. 14 is a right side elevation view of the ice crusher in FIG. 9.

FIG. 15 is a top plan view of the ice crusher in FIG. 9; and, FIG. 16 is a bottom plan view of the ice crusher in FIG. 9. The broken lines in the drawings are employed to show unclaimed portions of the ice crusher, and form no part of the claimed design.

1 Claim, 16 Drawing Sheets
